Detroit, Mich., a corporation of Michigan

Application December 23, 1932, Serial No. 648,692

14 Claims. (Cl. 154—2)

This invention relates to panel material, particularly for upholstery and automobile coach work, but is equally useful in numerous other applications.

5 The principal object of the invention is to produce panelling by an efficient and economical method and wherein the product will possess all the necessary requisites of an article of this character.

10 Heretofore, various types of panelling have been used and have developed serious objections which it is the aim of this invention to overcome.

For example, there are structures wherein a 15 suitable number of spaced slides or keyways are attached to a base, and thereafter a spring clip is attached to the panelling by engagement in each slide or keyway. Another expedient with which we are familiar, is the provision of an elongated 20 slot in a foundation or body terminating in an opening through such base or body, whereby a spring clip or fastener may be inserted after the trim cloth has been affixed to the base and before the completed panelling is attached to a body 25 frame. In other constructions where the fastener means is attached to the panel before application of the trim cloth, lateral movement is allowed 30 the studs or fasteners so that they are not held fixed and in the precise required locations.

35 Among the principal objections to conventional panelling are the relatively heavy, and hence undesirable, thick, board now required for strength and to afford a support for the clip fastening means. That is, such fastening means must be attached to the board by prongs or studs, which latter must not project through the board and thereby mar the trim or other surface appearance. Such board or base, moreover, has a tendency to warp due, we believe, to exposure to moisture and 40 temperature conditions occasioned by seasonal changes. Another difficulty with the usual paneling is encountered in the assembling of the final article preparatory to its application to the body frame. For instance, where the clips are inserted 45 as the final step in the production of the article, this must be accomplished at the automobile assembly plant and is objectionable for several reasons. First, the necessity of inserting the clips results in delay and holding up of the assembly 50 line, as where the clips do not fit easily into the keyways. Second, in such cases it is necessary that the clips be driven or forced in such a manner that the hands of the workmen are frequently injured. Third, because of the need for haste at the assembly line, the clips may be only partially 55

inserted or improperly placed in position so that they are not located in such manner as to properly register with the openings or sockets in the body frame. This latter is, of course, a very important objection in that where the clips are not uniformly 5 located, the entire panelling must be discarded. A further objection to conventional constructions resides in the use of slidably or movably positioned fasteners or studs, since where such construction is employed, the fasteners work loose and move 10 about to become unduly strained and distort the panel. Also, rattling and squeaking frequently ensues, and, as we just pointed out above, the sliding or movable connection of the clips or fasteners also renders it extremely difficult to prop- 15 erly locate them for registration with the openings in the body frame. In other words, by such constructions, wherein substantial sliding of the base or foot of the fastener or clip is permitted, it is 20 usually impossible to obtain (1) a uniform loca- 25 tion or registered relation of the fasteners or clips, and (2) to be assured that they are permanently 30 fixed in position, since such clips or fasteners are 35 movable as a whole.

We have mentioned above also the necessity, 25 in conventional structures, of applying the clips as the final step in the automobile plant before the panelling is attached to the body. This is necessary in order that the panels may be stacked at the factory and conveniently shipped to the 30 automobile plant, and the final operation of inserting the clips is both expensive, tedious, and unreliable, insofar as it affects the positioning of the clips.

35 We have found, furthermore, that conventional structures are subject to disastrous and expensive breakage when, for any reason, the panelling must be removed and replaced, that is to say, the means for fastening the clips to the board is often torn away or the clips or 40 fasteners themselves are mutilated. Also, in constructions where the clips or studs project through openings in a fibrous board, there is always the possibility of tearing or wearing the opening, thus affecting the proper fit of the panel and mutilating the board. Such openings objectionably affect the appearance of the trim, in that a smooth continuous surface is not possible 45 and this condition is aggravated when any tearing or disruption of the openings takes place. 50

We have developed a coach work or upholstery panel wherein (1) the bases of the fasteners or studs are preferably fixed in position and the shank and head are freely movable in all directions, and (2) a panel suitably reinforced to 55

assure both long life and maximum resistance to conditions normally present and surrounding the use of articles of this character.

With the panelling now to be described, we have taken into consideration the various, heretofore insuperable, difficulties and have obtained, by an efficient and economical method, a product having (1) increased wearing qualities, strength and resilience, i. e., resistance to shocks or blows; (2) greater ease of application and wherein the accurate location or registration of the fasteners with the body frame openings is assured; (3) qualities enabling the panelling to be permanently deformed and accommodate itself to particular conditions and shapes; and such qualities which also allow the panelling to be embossed and to permanently retain various designs; (4) substantially sound absorbent properties; (5) a minimum of adhesive, in fact, free as far as possible from any objectionable or unreliable gluing operations, the structure being positively united or secured together; (6) the fasteners precisely located and fixed with no opportunity for moving or sliding and having such fasteners provided with shanks freely flexible in all directions; and (7) reinforcing means to prevent any possibility of warping.

The product of the present invention, moreover, is assembled at the factory as a unit having the body frame fastening means fixed in position and the complete panels are stacked and shipped to the automobile plant where they can be applied from the assembly line without any further operations.

35 The present panelling, moreover, provides a smooth base for the fabric, or other trim as well as a coating, such as a suitable lacquer or finish.

Referring to the drawings,

Figure 1 is a view showing a door panel in 40 position;

Figure 2 is a view showing the various parts of the panel in position to be assembled and upon a suitable press;

Figure 3 is a sectional view of our improved 45 panel;

Figure 4 is a similar sectional view showing the panel applied to a door frame;

Figures 5 to 10, inclusive, illustrate various 50 types of reinforcing layers, in united relation to the board or base;

Figure 11 is a view representative of the various boards illustrated in Figures 5 to 10 having a coating of lacquer or other finishing material applied to the metallic surface;

55 Figure 12 is a view of a modified type of panelling wherein the board is attached to opposite sides of the reinforcement;

Figure 13 is a modification in which the reinforcement is applied in the form of strips to the 60 marginal surface portions of the board;

Figure 14 is a section on the line 14—14 of Figure 13; and

Figure 15 is a modified construction wherein 65 the reinforcement is employed, as a marginal or edge binding, of substantially U-form.

Referring to the drawings, in Figure 1 we have 70 illustrated a panel applied to the rear door of an automobile. This panel comprises a base 10 which in some cases is formed of sound absorbent material, and is usually constructed of a material having a suitable body or rigidity such as cardboard, fiberboard, pressed board, a felted

75 material, or paper-like material which is treated in such manner as to be rendered water and moisture resistant. Also, we use paper-like ma-

terials of fibers, cork and fibers, or laminated structures having bonded layers of fibers and cork and fibers including materials described in United States Patents Nos. 1,888,409 and 1,888,410.

We attach to this board a perforated sheet 11 of thin metal, such as sheet steel, copper, or alloy metal and which sheet is provided with struck-up projections of various types and openings adjacent thereto. The projections are embedded in the board by pressure, as shown in the drawings, and preferably terminate below the opposite surface of the board. In this manner, one surface of the panel comprises a perforated metal sheet, while the opposite surface is smooth and unobstructed, so as to nicely receive and support a trim of fabric or a finish coating.

The projections firmly unite the metal sheet and board and obviate the use of adhesives and glues, which, in many instances, prove unreliable when exposed to weather, as in the case of the doors of motor vehicles.

In Figure 5, we have shown projections struck up in the metal sheet in the form of protuberances 12 and tangs projecting from the apices thereof and forming openings 13. This construction is also shown in Figure 10, wherein the tangs extend to the outer surface of the board and are bent over to lie within the plane thereof and form a smooth unobstructed surface. A similar construction is also shown in Figure 12, wherein the metal reinforcing sheet constitutes a core.

In Figure 11, we have illustrated a board, as shown in Figure 5, having protuberances and tangs wherein the tangs do not extend to the outer surface of the board, and wherein the metal surface is provided with a coating of lacquer or other finish of suitable color. This construction, shown in Figure 11, is highly suitable for foot boards or cowl panels of automobiles, a relatively stiff or coarse paper or fiber web suitably waterproofed being preferably employed as the base, and the material being useful in many other similar applications. It may be tacked or glued in position or supplied with studs or fasteners as herein shown and described. It will be understood that the coating which we will designate by the numeral 14 may be applied to any of the several constructions illustrated in Figures 5 to 12, and, in fact, is also applied to the opposite surface of the board, as well as to the perforated metal layer.

In Figure 6, the projections take the form of a relatively long tang at one side of the opening and a shorter tang at the opposite side, while in Figure 7 the tangs are of equal length. In Figure 8 single tangs or tongues are struck up from the sheet and in Figure 9 such tangs extend through and have their ends bent over and clenched to lie in the plane of the opposite surface of the board and form a smooth unobstructed surface. As stated, the various types of projections serve to bind the board to the reinforcement. The perforated sheet is stiffened by reason of this construction, so that relatively thin gauge metal may be employed, and the projections impart strength to the board. By reason of this construction, a relatively thin board may be employed effecting a saving in this material and the metal reinforcement effectually prevents any possibility of warping.

The tangs are arranged in rows and in some cases those of one row are in staggered relation to those of an adjacent row.

The projections are struck up in the metal sheet at a multiplicity of closely spaced points throughout the area of the sheet, thereby forming closely compacted or spaced perforations and projections, the metal sheet preferably, but not always, being coextensive with the base.

Further, the use of a metal reinforcing with these spring-like tongues or projections imparts a resiliency to the board and panel, whereby it 10 will receive shocks and blows without becoming permanently deformed.

At the same time, however, since the board and the metal layer are relatively thin, the panel may be bent or shaped to accommodate itself to 15 various configurations or conditions encountered and when so deformed or shaped, will retain its new configuration. This is likewise true when designs or other figures are embossed in the panel material.

20 Since it is quite customary to form pockets on the panel, the metal sheet provides an effective anchor for the stitching of said pockets.

Referring to Figure 2, we have illustrated the board, the reinforcement and a layer of trim material 16 disposed in a suitable press, preparatory to forming the assembled panel. The press is formed with embossing dies for producing a suitable design or indentation 17.

Referring to Figure 3, we have illustrated a 30 panel after it has been formed by the compressing operation shown in Figure 2. It will be observed that we utilize fastening members in the form of studs having enlarged head portions 18, reduced shanks, and wide, preferably flat base portions 19. The base portions are disposed in spaced recesses 20 formed in one surface of the board, such recesses being of a depth to allow the bases of the studs to lie flat and have their upper surfaces preferably flush with the surface of the 40 base to prevent formation of ridges in the reinforcing layer or the base layer when combined by pressure, whereby the metal about the base of the stud will lie substantially flat and cooperate with the base to clamp the base of each stud firmly in position. The recesses are of a size to receive the base of each stud and substantially prevent any sliding movement thereof in any direction. The studs are inserted through openings 20' in the metal reinforcing layer, which openings are spaced in accordance with the openings or sockets 22 in the body frame 21 and the spacing of said recesses 20, the openings 20', 22 being of a size to pass the head and shank of the stud but prevent any shifting movement of the stud. 50 In other words, when the stud or fastener is positioned as shown in Figure 3, with its foot or base clamped between the metal layer and the facing layer, the base of the stud or fastener is substantially fixed and is not capable of any substantial lateral or other sliding movement.

The studs or fasteners are preferably constructed of material which will permit them to flex or bend freely in all directions, such material being resilient, flexible, or compressible and of 60 sufficient strength to properly and firmly support the panel without sagging. We use studs or fasteners made of such materials as molded rubber, molded cork, molded cork and rubber mixtures, as well as flexible metal fasteners or studs having compressible heads, and flexible and resilient types of fasteners, there being many commercial varieties of so-called snap fasteners available. We prefer a stud or fastener which is bendable in all directions but which will not permanently deform.

The resilient and flexible studs have their bases fixed in position, such bases being, for all practical purposes, immovable. The studs or fasteners are bendable about their substantially fixed bases in all directions to take care of any irregularities in registration of the studs with the sockets or openings in the frame. This condition often exists initially, and frequently results from use of the vehicle, due to loosening up or shifting of the body frame, and we find that a 10 stud having a resilient and flexible shank is highly efficient. Again, such studs provide a cushion support for the panel body, firmly holding it in position and avoiding squeaking or rattling. They permit, moreover, of a very easy attachment or 15 positioning in the body frame receiving openings and sockets, a simple tapping usually being sufficient to insert them. Since the bases or feet of the stud are firmly and permanently held, the panel is easily removable in that the heads of 20 the studs will spring out of the sockets upon application of a light pressure or leverage. Equally important in this connection is the practical elimination of the possibility of tearing the stud from the panel and thereby ruining the installation. 25

The head of the stud or fastener may be of any suitable configuration, determined by the opening or socket in the body frame in which it is adapted to be inserted. In Figure 4, I have illustrated 30 the panel applied to the body frame 21 with the stud extending through an opening 22 therein and having its enlarged head engaging the opposite wall of the frame.

By the construction described, when the parts 35 are compressed together, the reinforcing layer is firmly affixed to the board clamping the stud in position and since the opening in the reinforcement is just large enough to receive the stem of the fastener, the fastener is firmly fixed and located. Moreover, since a flexible stud of rubber or other penetrable material is employed, the projections will extend into the base of the fastener to additionally anchor it in position. Where a resilient stud of metal is employed, it 45 will be understood that the opening, likewise, will be of a size to pass the head and shank, and the foot will act as a stop for the projections, bending them over and providing in effect a cushion for the base of the fastener when the parts are 50 compressed together as shown in Figure 3.

In producing the recesses 20 and openings 20' respectively, in the board and reinforcement, we use similar dies wherein, when the two layers are assembled, the openings exactly and precisely register with the recesses or vice versa.

With the several parts in position as shown in Figure 2, the operation of the press will serve to unite the board 10 and reinforcement 11 and we apply a water, moisture and temperature resistant glue or adhesive coating to either of the adjacent opposed surfaces of the board or trim, or to both of such surfaces, so that the trim is likewise united to the smooth, unobstructed surface of the board. In this connection, the press will carry suitable embossing dies 23 to produce the desired configuration 17, and the dies will also be formed to receive the studs 18, which, as will be understood, are inserted in the openings in the metal layer preliminary to the uniting operation.

In Figures 13 and 14, we have shown a construction wherein strips 25 of the metal reinforcement are applied at the marginal edges of the board and wherein the studs or fasteners are 75

positioned in the manner herein described. This expedient is used where it is not desired to have a metal layer coextensive with the board but the closely compacted projections are employed as with the coextensive metallic layer shown in the other figures of the drawings.

In Figure 15, we have illustrated a modification wherein the reinforcing takes the form of a binding of substantially U-shape 28 about the exposed edge of the board with the projections embedded in the board, as heretofore described, and the stud or fastener similarly clamped in accordance with the other structures.

In employing a flexible or resilient stud such as one of rubber, we are enabled to apply the stud at the time of manufacture of the panel, and thereafter stack the complete panels for shipment to the automobile plant and assembly line. The studs will readily flex for this purpose and assume their normal position when the pressure is removed in a stack.

By providing a perforated metal reinforcement and particularly one having a multiplicity of perforations and projections closely spaced over its entire area, the panel is strengthened and rendered sound absorbent.

It will be observed that the studs or fasteners are fixed in proper spaced relation and for all material purposes their bases are immovable, as distinguished from prior structures wherein the studs are bodily movable as a whole.

As heretofore stated, instead of using a fabric trim 16, we coat the smooth surface of the board, as well as the metal surface, with any suitable finish or lacquer.

In Figure 3, we have illustrated the free marginal edges of the trim or fabric turned over and united to the metal sheet. This union is accomplished through the medium of a suitable water-proof adhesive or glue similar to that which will be applied for uniting the trim to the face of the base of the board. Such overlapping portion provides a cushion or layer 28 between the panel and the base of the frame 21 as in Figure 4.

It is to be observed that the fastener is positioned without the necessity of piercing the board and also that the tongues or projections preferably do not extend to the opposite opposed surface of the board. Where the projections extend through, they are bent over to be flush with or lie within the plane of the exposed surface of the board, their free ends being preferably clenched into the base with the end edges not exposed and the surface is free of projecting portions. Therefore, the board has a smooth unobstructed surface, and the trim is very nicely applied and fits the board to obtain a very desirable panel.

The studs or fasteners will be applied usually along three sides of the panel, but may be applied to one, two, or all four sides, and in such number as required.

In Figure 4, where we have shown the panel in section applied to the body frame, it will be understood that while the frame is illustrated as having an opening 22 receiving the fastener 18, this may take the form of a rigid or resilient socket as desired. In fact, various types of separable fastener constructions may be used as found most convenient, preferably, however, of a flexible type, that is, a fastener which may be flexed or bent without permanently or objectionably distorting.

It is to be noted that in any of the embodi-

ments of the invention, the metal layer or reinforcing constitutes a continuous means for fixing the spaced relation of the studs or fasteners. That is, the openings in the continuous sheet or strip of reinforcement assure the proper alignment and registered location of the fasteners. The reinforcing and the walls of the openings cooperate with the board to prevent any substantial movement of the bases of the studs or the stud as a whole where a rigid stud is used, but do not interfere with the flexing of the shanks of the resilient or bendable studs.

While we have indicated that the bases of the studs are fixed, we may, in some cases, enlarge the openings in the metal and the recesses in the board or base to allow for a limited shifting movement of the studs. Also the stud may project through openings in the base formed centrally of the recesses 20 and the reinforcing layer of metal receive the trim or coating.

We prefer, however, that the studs project through the reinforcing layer as shown leaving the base with a smooth unobstructed surface.

In assembling the panel, as in Figure 2, it will be noted that the layers are superposed so that the tangs extend in one direction and the studs in the opposite direction. Where the studs project through the base, both extend in the same direction, and the trim is superposed on the metal layer. As stated, a stratum of suitable adhesive is disposed between the trim and the layer to which it is applied.

We will, in some cases, also unite a metal layer, as shown herein, to each side of the base, one such layer receiving the trim or coating and the studs extending out from the opposite layer as shown and described.

The tangs or projections 12 may be of any suitable length and the board likewise of varying thickness, but we prefer a thin board and hence the tang or tangs and protuberances are of minimum length to obtain the desired result.

The metal is heat resistant and heat conductive and the tangs tend to transfer heat away from the interior of the car.

In some cases, means are provided operating with the press, to fold over the marginal portions 28 of the trim and unite the same to the adjacent layer of the panel simultaneous with the pressing operation.

Various modifications of the invention may be resorted to, all of which are comprehended within the appended claims.

We claim:—

1. A panel comprising a base layer and a reinforcing layer, and fastening means freely flexible in all directions, said fastening means comprising studs, one end of each stud fixed to the panel and extending through openings in the reinforcing layer.

2. A panel comprising a base having one surface substantially smooth and unobstructed and a metal layer having a multiplicity of struck up projections embedded in said base and uniting said layer thereto, forming a perforated metal surface on the opposite side of said base, and studs or fasteners extending from said panel and clamped in fixed spaced relation between said metal layer and said base.

3. A panel comprising a base having one surface substantially smooth and unobstructed, and a metal layer substantially coextensive therewith having a multiplicity of struck up projections extending throughout the area of the metal layer, and embedded in said base and uniting said

- layer thereto, forming a perforated metal surface on the opposite side of said base, and spaced flexible studs or fasteners extending from the marginal area of the panel on one side thereof.
5. A panel comprising a base having one surface substantially smooth and unobstructed, and a metal layer substantially coextensive therewith having a multiplicity of struck up projections extending throughout the area of the metal layer, and embedded in said base and uniting said layer thereto, forming a perforated metal surface on the opposite side of said base, and spaced studs or fasteners of rubber extending from the marginal area of the panel on one side thereof.
10. A panel comprising a base having one surface substantially smooth and unobstructed, and a metal layer having a multiplicity of struck up projections embedded in said base and uniting said layer thereto, forming a perforated metal surface on the opposite side of said base, and spaced studs or fasteners extending through openings in the marginal area of the metal layer and confined thereby.
15. A panel comprising a base having one surface substantially smooth and unobstructed, and a metal layer substantially coextensive therewith having a multiplicity of struck up projections extending throughout the area of the metal layer, and embedded in said base and uniting said layer thereto, forming a perforated metal surface on the opposite side of said base, and spaced studs or fasteners extending from the marginal area of the panel, said studs or fasteners having enlarged bases, the bases of said studs or fasteners being clamped in position between said metal layer and said base.
20. A panel comprising a base having one surface substantially smooth and unobstructed, and a metal layer substantially coextensive therewith having a multiplicity of struck up projections extending throughout the area of the metal layer, and embedded in said base and uniting said layer thereto, forming a perforated metal surface on the opposite side of said base, and spaced studs or fasteners extending from the marginal area of the panel, said studs or fasteners having enlarged bases, the bases of said studs or fasteners being engaged on opposite sides by said metal layer and said base to clamp the studs in fixed position, and said studs extending through openings in said metal layer.
25. A panel comprising a relatively thin fibrous base having one surface substantially smooth and unobstructed, and a relatively thin metal layer substantially coextensive therewith and having a multiplicity of struck up projections extending throughout its area, the projections embedded in said base and uniting said layer thereto, forming a perforated metal surface on the opposite side of the base, and flexible fasteners or studs having enlarged bases interposed between said base and said metal layer and held
- clamped in fixed position thereby, said studs or fasteners extending through openings in the metal layer, and a layer of trim material adhesively united to the smooth and unobstructed surface of said base and having its marginal edges 5 united to said metal layer.
9. The method of making a panel which comprises superposing a layer of perforated metal having projections and confining studs or fasteners upon a layer of base material superposed 10 on a layer of trim and between which latter layers is a stratum of adhesive, with the projections extending toward the base and the studs or fasteners extending in the opposite direction, uniting the respective layers by pressure and embedding the projections in said base and clamping the studs or fasteners in position.
10. A panel comprising a layer of base material having a substantially smooth continuous surface on one side, a multiplicity of recesses 20 on the other side of said layer, a metal layer having openings therein and united to the base layer on said last mentioned side, and studs having their bases in said recesses and their stems extending through said openings.
11. A panel comprising a layer of base material having a smooth continuous surface on one side, a multiplicity of recesses on the other side, a metal layer having openings therein and provided with projections embedded in said base 30 layer for uniting the layers, and studs having their bases in said recesses and their stems extending through said openings.
12. A panel comprising a layer of base material having a substantially smooth continuous 35 surface on one side, a multiplicity of recesses on the other side of said layer, a metal layer having openings therein and united to the base layer on said last mentioned side, and studs flexible in all directions having their bases in said recesses and their stems extending through said openings.
13. A panel comprising a layer of base material having a substantially smooth continuous 45 surface on one side, a multiplicity of recesses on the other side of said layer, a metal layer having openings therein and united to the base layer on said last mentioned side, and rubber studs having their bases in said recesses and their stems extending through said openings.
14. A panel comprising a layer of base material having a smooth continuous surface on one side, a layer of trim cloth covering said side, a multiplicity of recesses on the other side of said layer, a metal layer having openings therein 55 and united to the base layer on said last mentioned side, and studs having their bases in said recesses and their stems extending through said openings.
